BRACELET CHAIN

John F. Sand, Newark, N. J., assignor to Gemex Company, Union, N. J., a corporation of New Jersey

Application May 18, 1949, Serial No. 2,717

Term of patent 7 years

(Cl. D45—4)

To all whom it may concern:

Be it known that I, John F. Sand, a citizen of the United States and a resident of Newark, in the county of Essex, State of New Jersey, have invented a new, original, and ornamental Design for a Bracelet Chain, of which the following is a specification, reference being had to the accompanying drawing, forming a part thereof.

In the drawing,

Figure 1 is a top plan view of a portion of a bracelet chain showing my new design; and

Figure 2 is a side elevational view thereof.

The bottom links are conventional in appearance.

I claim:

The ornamental design for a bracelet chain, as shown and described.

JOHN F. SAND.
